ORNAMENTAL DISPLAY DEVICE

Harry W. Tucker and William S. McLeish,
New York, N. Y.

Application October 19, 1934, Serial No. 749,026

7 Claims. (Cl. 40—152.1)

This invention relates to ornamental display devices and is particularly adapted to the display of pictures, signs and similar articles.

An object of the invention is to provide an improved apparatus for displaying flat articles which will present an attractive appearance.

Another object is to provide an improved display apparatus which will be simple in construction and economical to manufacture.

Another object is to provide an improved display apparatus with which pictures, signs or the like may be easily assembled.

Another object is to provide an improved display apparatus in which objects lying in different planes may be displayed.

Other objects will hereinafter appear.

The invention will be better understood from the description of several practical embodiments thereof, illustrated in the accompanying drawing, in which:

Figure 1 is a perspective view of one embodiment of the invention;

Figure 2 is a central sectional view taken on line II—II thereof;

Figure 3 is a view similar to Figure 2 showing another embodiment of the invention;

Figures 4 and 5 are fragmentary views corresponding to the upper portion of Figure 2 but showing further modifications of the apparatus;

Figure 6 is a perspective view of another embodiment;

Figure 7 is a sectional view taken on the line 7—7 of Figure 6; and

Figure 8 is a view similar to Figure 7 of still another embodiment of the invention.

This application is a continuation of our copending application Serial No. 648,531 filed December 23, 1932, for Ornamental display devices, as to all subject matter common to both applications.

In Figures 1 and 2 a device is shown consisting of a base 1 which may be of wood, metal or other solid material, and is provided with two slots 2 and 3 extending downwardly from its upward surface. These slots are adapted to receive the lower ends of sheets 4 and 5 which constitute the pictures, signs or the like, and which may be of paper, cardboard, celluloid or any desired thin flexible material.

The slots converge upwardly, being disposed at a more acute angle than that which would be assumed by the sheets if these were allowed to remain in two planes with their upper edges abutting and their lower edges separated by the distance between the slots. The sheets 4 and 5,

therefore, press upon each other at or near their upper edges, bending themselves into slightly concave form which causes them to be frictionally held within the slots.

A strip 6 of thin flexible material, such as sheet metal, celluloid, or the like, has its lower end secured within the base 1, as by a nail or tack 7. Its upper end is provided with a ring 8 or other shaped piece, which may be secured to it in any desired manner as by adhesive, soldering, rivets 10 or the like, and serves as a handle by which the entire device may be picked up. The thickness of strip 6 is slight and serves to separate the sheets 4 and 5 only negligibly at the central portions of their upper edges between which it passes. 15

Instead of two continuous sheets, it will be obvious that mats such as illustrated in our above-mentioned copending application may be used and the term "sheet" will therefore be used to include both single integral sheets and compound sheets 20 each comprising a mat, frame, cutout sheet, or the like.

In Figure 3 a device is illustrated having a base 11, substantially identical to the base of the first figure, provided with slots 12 and 13 and arranged 25 to hold sheets 14 and 15 which constitute the articles to be displayed. A central post or mast 16 is provided having a reduced lower end 17 which is secured within a hole in the base by friction or adhesive or in any other desired manner. The upper end of the mast may be provided with a ring 18. The post or mast 16 is rigid and serves 30 to hold the sheets or cards 14 and 15 in flexed position, rather than permitting them to bear upon each other.

In Figure 4 a mast 26 is shown as provided with an enlarged top 28, the juncture of the mast and the top forming shoulders 28a and 28b, under which the upper edges of the sheets or cards 24 and 25 may be inserted, so that the post or mast 40 serves to hold these cards down within the slot of the base.

In Figure 5 the upper end of the post or mast 36 is below the upper edges of the sheets or cards 34 and 35, and so by them concealed from view, while serving to hold these sheets in the desired flexed position.

In Figures 6 and 7 a device having two posts or masts is illustrated. It has a base 41, in general 50 similar to the bases of figures previously described, slots 42 and 43 holding the lower ends of the sheets 44 and 45, while the two posts 46 are arranged near the ends of the base. They are shown in Figure 7 as having reduced ends 47 55

extending through apertures in the base and riveted over as indicated at 47a.

Each post has extending through it a slot 46a and in these slots are supported cards or pictures 49. The sheets 44 and 45 in this modification are made of transparent material or have apertures formed through them so that parts of sheets 49 may be seen. Obviously with transparent sheets, opaque borders or the like may be provided, or it is possible to provide such sheets with colors or illustrated portions having some relation to the illustrations or the like on sheets 49, and serving in effect as a foreground while sheet 49 serves as a background.

15 The posts 46 may be made integral, as by being formed with a single piece of rod or the like having a looped portion 48 which serves as a handle, or connected in any other desired manner.

20 In Figure 8 a post or mast 56 is illustrated having a plurality of notches 56a and 56b formed in it. The sheets or cards 54 and 55 bear upon the post as in the form above described, while inner sheets 59 are sprung into place with their edges in the notches and so frictionally held. The notches also permit the use of different sized sheets 59.

25 Posts of the form illustrated in Figure 8 may be used in pairs, as are the pairs 46, or singly, as is post 16, and like the embodiment illustrated in Figure 6 or 7 these make possible the use of the outer sheets 54 and 55 to serve as a frame by having transparent or cutout central portions or to act as a foreground.

30 While we have described several illustrated embodiments of our invention in some particularity, obviously many others will readily occur to those skilled in this art, and we do not, therefore, limit ourselves to the precise details shown and described but claim as our invention all embodiments, variations and modifications thereof coming within the scope of the appended claims.

We claim:

1. A display device comprising a piece of flexible resilient material, a base provided with a slot adapted to receive the lower end of said sheet, a rigid post fixed to said base, the slot being of a depth a plurality of times its width and disposed at a lesser angle to the base than would be assumed by the sheet if left free with its upper end touching the post and its lower end separated from the post by the same distance as the slot is spaced therefrom, whereby the sheet is caused to flex itself and bear against the post.

2. A display device comprising two sheets of flexible resilient opaque material and a base provided with slots adapted to receive the lower ends of said sheets and disposed at a more obtuse angle than would be assumed by the sheets if left free with their upper ends touching each other and their lower ends separated by the same distance as the slots, whereby the sheets are caused to bear upon each other and mutually flex each other.

10 3. A display device comprising two sheets of flexible resilient material, supporting means common to both said sheets causing them to bear upon each other and mutually flex each other, and a handle connected to the supporting means and extending beyond the edge of the sheets remote therefrom.

4. A display device comprising a sheet of flexible resilient material and through portions of which an object there behind may be viewed, a supporting base, and a post secured to said base, the base receiving one end of the sheet and causing it to bear upon the post, the post having means for supporting a second sheet behind said first mentioned sheet in a position to be viewed through the above referred to portions of the first mentioned sheet.

5. A display device comprising a sheet of flexible resilient material, a supporting base, and a post secured to said base, the base receiving one end of the sheet and causing it to bear upon the post, and the post having slots for supporting a second sheet behind said first mentioned sheet.

6. A display device comprising a sheet of flexible resilient material, a supporting base, and a post secured to said base, the base receiving one end of the sheet and causing it to bear upon the post, and the post having notches for supporting a second sheet behind said first mentioned sheet.

7. A display device comprising a sheet of flexible resilient material having portions through which an object behind the sheet may be viewed, a supporting base, and a plurality of posts secured to said base and arranged on opposite sides of said portions of the sheet, the base receiving one end of the sheet and causing it to bear upon the posts, the posts having means for supporting a second sheet behind said first mentioned sheet, said second sheet extending between said posts and being visible through said portions of the first mentioned sheet.
